(57) CLAIM

The ornamental design for a vehicle grille, as shown and described.

DESCRIPTION

The contents of concurrently filed application Ser. No. 29/363,626 are also hereby incorporated by reference.

FIG. 1 is a perspective view of a vehicle grille showing our new design;

FIG. 2 is a front elevational view thereof;

FIG. 3 is a top plan view thereof; and,

FIG. 4 is a side elevational view thereof.

The broken line showing of the lozenge-shaped marquee forms no part of the claimed design.
